UNITED STATES PATENT OFFICE.

EARL H. TATE, OF LOS ANGELES, CALIFORNIA.

INCANDESCENT LAMP.

1,032,961.

Specification of Letters Patent.

Patented July 16, 1912.

Application filed May 4, 1911. Serial No. 624,927.

To all whom it may concern:

Be it known that I, EARL H. TATE, a citizen of the United States, residing at Los Angeles, in the county of Los Angeles and State of California, have invented certain new and useful Improvements in Incandescent Lamps; and I do declare the following to be a full, clear, and exact description of the invention, such as will enable others skilled in the art to which it appertains to make and use the same.

This invention relates to incandescent electric lamps, and the object of the same is to produce improvements in the means for connecting the base with the bulb, the stem and the terminals with the neck of said bulb, and the filament hangers with the stem; and furthermore to improve the construction of said hangers themselves. These objects are accomplished by the construction hereinafter more fully described and claimed and as shown in the drawings wherein—

Figure 1 is a perspective view of the lamp partly in section; Fig. 2 is a central vertical section through the same; Fig. 3 is a detail horizontal section on the line 3—3 of Fig. 2; Fig. 4 is a similar view taken on the line 4—4 of Fig. 2; Fig. 5 is a plan view of one of the hangers on an enlarged scale.

In the drawings the numeral 1 designates the base having exterior screw threads as usual to engage the lamp socket, and having around its lower end a flange 2 containing an upstruck groove 3 within which lies an insulating cushion or ring 4 which bears upon the bulb 5 when the latter is in place. The bulb is intended to be made of glass as usual, and its neck is molded within the metallic part of the base 1, while its body rests within and is gently supported by the ring 4 so that vibrations to which the lamp is subjected are less likely to disconnect the glass and metallic parts or to break the vacuum in the former.

The numeral 10 designates a stem, preferably tapering downward from its head 11 as best seen in Fig. 3. These parts are by preference formed of a single piece of glass, and the head has corrugations on its exterior and is intended to be molded within the neck of the bulb, the terminal wires 12 being laid across said corrugations and molded into place so that they are reliably held out of contact with each other. The outer end of one wire is connected with the metallic part of the base 1 and the outer end

of the other wire with the contact 13 as usual. Mounted upon and by preference molded with said stem are two collars each consisting of two disks spaced slightly apart for a purpose to appear. The upper collar carries the crescent-shaped hangers, and the lower collar carries the anchors which are simply wire hooks. The hangers and anchors are of metal and are molded between the disks which form each collar, and thus they are reliably held apart by the insulating stem 10 and are also held reliably spaced in two horizontal planes whose distance apart will depend upon the size of the lamp. By preference the upper collar is larger than the lower one as seen in Fig. 1.

The hanger best seen in Fig. 5, comprises a wire frame 20 curved in nearly a half circle and having an arm 21 projecting from the center of its length, and two pins 22 projecting inward from its extremities toward each other, and a bow 23 also of wire and curved on a larger arc than that of the frame, this bow having eyes 24 at its extremities which are mounted loosely on said pins 22. The arm 21 forms a stem which is inserted between the two disks of the upper collar and molded therein, and as seen there are several such hangers disposed around this collar. Molded between the lowermost disks are hooks 27 also of wire and projecting outward, and as seen there are several of these standing in a horizontal plane through the lower end of the stem 10. Finally the filament 30 is led from a pin 22 of one hanger downward around a hook 27 and then up to the nearest pin 22 of the next hanger, from which point the current must pass through the frame 20 to the opposite pin 22 of this hanger, when the next filament occurs. The terminal wires 12 are connected up as best seen in Fig. 1. I have found that this means of supporting the filament renders the latter less liable to breakage during the ordinary and extraordinary uses of an electric lamp, than where the extremities of the filament are molded into the glass so that vibrations and expansion and contraction are necessarily required to take place within the length of the filament itself. By making the upper collar larger than the lower, the general contour of the series of filaments will be slightly conical with the smaller truncated end of the cone at the bottom. The hooks 27 may be made as long as possible within

the bulb 5, and in fact, they could be quite long so that the lower collar would be larger than the upper and thereby the smaller end of the conical group of filaments would be 5 at the top. The use of a bow 23 between the pins 22 of each hanger, loosely connected at its end with said pins, I find to be of considerable advantage where each filament attached to one pin leads to an adjacent pin 10 of another hanger, because this disposition of the filaments tends to draw the frame 20 outward and such tendency is to an extent resisted by the bow 23. The use of a curved frame 20 instead of a hanger-frame whose 15 arms are straight, I find to be beneficial because it reduces vibration of the filament by jars of the lamp support, as it is obvious that a straight member cannot yield longitudinally whereas a curved member can. 20 What is claimed as new is:

1. In an incandescent electric lamp, the combination with a glass stem having an enlarged head provided with external annular corrugations, the terminals leading across 25 the latter, and the bulb whose neck is molded around said head; of the tubular metallic base surrounding said neck, and the filaments carried by said stem and connected with the inner ends of said terminals. 30
2. In an incandescent electric lamp, the combination with a glass stem having collars upon it of different sizes; of hangers molded in and projecting beyond the edge of the upper collar, hooks molded in and

projecting beyond the edge of the lower 35 collar, a conical group of filaments connecting said hangers and hooks in series, and the terminal wires connected with the filaments.

3. In an incandescent electric lamp, the 40 combination with a bulb, and a glass stem molded in the neck of the latter and having collars upon it; of hangers and hooks molded in and projecting beyond the edges of the upper and lower collars, a group of 45 filaments connecting said hangers and hooks, and the terminals molded between the neck of the bulb and the upper end of the stem and connected with said filaments.

4. In an incandescent electric lamp, the 50 combination with a stem having a pair of disks; of a crescent-shaped hanger comprising a curved wire frame having an arm projecting from its center and molded between said disks and pins projecting toward each other from its extremities, and a curved wire bow standing within the frame and having eyes at its extremities mounted on said pins, and the filaments connected with the latter. 55

In testimony whereof I have hereunto set my hand in presence of two subscribing witnesses.

EARL H. TATE.
